UNITED STATES PATENT OFFICE.

CARL WEBER, OF CHICAGO, ILLINOIS, ASSIGNOR TO CEMENT-GUN CONSTRUCTION COMPANY, OF CHICAGO, ILLINOIS, A CORPORATION OF ILLINOIS.

HOLDING-CLIP FOR CONCRETE-REINFORCEMENT.

1,311,932.

Specification of Letters Patent.

Patented Aug. 5, 1919.

Application filed April 8, 1918. Serial No. 227,159.

To all whom it may concern:

Be it known that I, CARL WEBER, a citizen of the United States, residing at Chicago, in the county of Cook and State of Illinois, have invented a certain new and useful Improvement in Holding-Clips for Concrete-Reinforcement, of which the following is a specification.

My invention relates to a holding clip for concrete reinforcement and has for its object especially to provide means for supporting the reinforcing structure of concrete walls before the concrete is applied thereto and before it has set. It has for a further object to furnish a combined supporting and spacing means for concrete reinforcement where the concrete is to be distributed by a cement gun or the like over the reinforcing structure fastened to and spaced from a plane and particularly a perpendicular surface. It has for another object to furnish a simple holding clip which can be quickly and easily secured to the supporting surface or member by a single nail or screw or the like.

My invention is illustrated more or less diagrammatically in the accompanying drawing, wherein—

Figure 1 is a front view of the clip in place supporting a metal netting;

Fig. 2 is a vertical section of the clip supporting a metal netting and secured to the holding surface; and

Fig. 3 is a perspective view of the clip secured in place and holding a reinforcing rod.

Like parts are indicated by like characters in all the figures.

A is the flat front surface or body of the clip perforated in its upper end at B to receive the nail C which holds the clip in place. Extending at right angles from the body or front of the clip are the limbs or flanges D, D, the outer edges of which may be at various angles to the front of the clip, but are preferably parallel thereto. These limbs are notched in their upper edges at E, E adjacent the front of the clip in such fashion as to be joined to the front of the clip only by the narrow necks F F, the breadth of which may be varied as required by the strength of the clip and the size and weight of the reinforcements to be supported. The clip is supported by the nail C which is driven through the aperture in the

front or top of the clip into the backing or supporting surface G. Obviously a screw, bolt or rod or similar fastening could be used if found necessary and efficient. The notches E, E in the upper edges serve as hooks to support the nettings, H, I, the rods J or other reinforcing members which may be used. The nail serves to hold the reinforcing members in place in the supporting notches. These drawings are in a sense diagrammatic and it will be understood that many variations in the form and disposition of the parts may be made without departing from the spirit of my invention.

The use and operation of my invention are as follows:—

My invention is especially fitted for use with that form of concrete wall structure which consists of the application of reinforcing members to a temporary backing of wood and the like and the subsequent distribution over the reinforcement and against the backing or supporting surface of fluid concrete driven from a cement gun. It can also be used in the application of metal lathing and the like for fire proofing walls and ceilings, and in the laying of cement or concrete floors, and in other methods of reinforcing and lathing not here described, for use with liquid or plastic materials. In its use the reinforcing members are supported or hooked into the notches in the clip limbs. The nail or other fastening is then inserted through the perforation in the clip front and driven into the backing wall, joist, beam or other structure over which the concrete or cement surface is to be applied.

The simple form of the clip will be noted and the ease with which it can be put in place. It needs only a single ordinary easily driven nail which is in great contrast to the ordinary type of spacing clip which may be itself a staple and which normally requires one or more supporting staples which are hard to drive in and easily bent. The nail also closes the top of the notches locking the reinforcement in place in the clip. Since the supporting nail is well above the bottom of the notches the clip naturally takes its efficient vertical position when applied to a vertical surface. When used on a horizontal surface the nail, since it closes the slot, prevents horizontal motion on the part of the reinforcing members. Obviously the

edges of the arms which engage the joist beam or backing could be inclined to the front of the clip or could be serrated or sharpened to grip the surface. I have shown only the simplest form where the edges are parallel with the clip front.

I have illustrated my invention where it is used with gun applied cement or concrete and on a vertical surface. Obviously my clip may be used for holding reinforcement on any kind of surface and the cement may be applied by any means and so, of course, it is understood that the specification is not to be limited to any particular situation, arrangement or kind of concrete.

I claim:—

1. As a new article of manufacture a U-shaped holding clip for concrete reinforcing members having a top provided at 20 its forward edge with a hole to receive the securing nail and two side limbs provided with bottom edges to give a long bearing against the wall and provided each with a deep notch entering from its front edge for the reception of the reinforcing member the parts so proportioned that the nail when in position closes the notches so as to hold the reinforcing member in place.

2. As a new article of manufacture a 25 U-shaped holding clip for concrete reinforcing members having a top provided at its

forward edge with a hole to receive the securing nail and two side limbs provided each with a deep notch entering from its forward edge the parts so proportioned that 35 the nail when in position closes the notches is out of contact with the member and lies between the two limbs.

3. As a new article of manufacture a U-shaped holding clip for concrete reinforcing members having a top provided at 40 its forward edge with a hole to receive the securing nail and two side limbs provided with bottom edges to give a long bearing against the wall and provided each with 45 a deep notch entering from its front edge for the reception of the reinforcing member the parts so proportioned that the nail when in position closes the notches so as to hold the reinforcing member in place, the U- 50 shaped clip being open on three sides and closed only on the top so as to permit free entrance of the mortar to fill the inside of the clip and surround and embed the nail.

In testimony whereof I affix my signature 55 in the presence of two witnesses this first day of April, 1918.

CARL WEBER.
